O. P. BENJAMIN

COMBINATION LAUNDRY TRAY BIB

Filed March 1, 1922

FIG. 1

FIG. 2

Inventor

Oscar P. Benjamin

By *Oscar P. Benjamin*

Attorneys

UNITED STATES PATENT OFFICE.

OSCAR P. BENJAMIN, OF DETROIT, MICHIGAN, ASSIGNOR TO CAPITAL BRASS WORKS, OF DETROIT, MICHIGAN, A CORPORATION OF MICHIGAN.

COMBINATION LAUNDRY-TRAY BIB.

Application filed March 1, 1922. Serial No. 540,123.

To all whom it may concern:

Be it known that I, OSCAR P. BENJAMIN, a citizen of the United States of America, residing at Detroit, in the county of Wayne and State of Michigan, have invented certain new and useful Improvements in Combination Laundry-Tray Bibs, of which the following is a specification, reference being had therein to the accompanying drawings.

This invention relates to combination laundry tray bibs and has special reference to that class of bibs, cocks, faucets, spigots or the like wherein warm and cold water commingle and have a common outlet into a laundry tray, tub or any other receptacle. Such bibs are ordinarily mounted on the rear wall of the laundry tray and communicate with hot and cold water supply pipes, there being two valvular structures by which the commingling of hot and cold water is controlled, and the spout or outlet member of the bib extends over the tray to discharge water therein.

The primary object of my invention is to provide novel brackets that may be easily and quickly attached to a tray wall to safely and firmly support the bib relative thereto, and the brackets may be reversed relative to the tray wall so as to place the bib in a desired position, provide clearance for wall structures and permit of connections being easily established with water supply pipes.

A further object of my invention is to provide bib supporting brackets of simple design that may be maintained in a sanitary condition, there being no places where soap, dirt and other matter can accumulate and render the fixture unsanitary and unsightly.

The above and other objects are attained by a mechanical construction that will be hereinafter specifically described and then claimed, and reference will now be had to the drawing, wherein—

Figure 1 is a side elevation of a bib supported relative to a tray wall;

Fig. 2 is a front elevation of the same.

In the drawing, the reference numeral 1 denotes a substantially U-shaped bib fitting connected to water supply pipes 2, one of these pipes supplying hot water and the other cold water. The ends of the bib fitting have bonnet valves 3 of a conventional

form controlling the commingling of hot and cold water centrally of the fitting 1, where there is a swiveled laterally disposed spout or outlet member 4. In order that the spout or outlet member may be freely swung in a lateral plane, I employ a swivel connection formed by extending the member 4 into a stuffing box 6, a suitable packing nut 8 being provided to form a water tight joint.

On the lower wall of the fitting 1, in vertical alinement with the water supply pipes 2 are channel shaped depending lugs 11, the channels of said lugs being longitudinally disposed and open at the rear faces thereof to receive the upper ends of brackets 12, which are attached to said lugs by screws 13^a or other fastening means preferably entered at the rear faces of the brackets. The upper ends of the brackets may fit against and support the lower wall of the fitting, and the lower ends of the brackets terminate in inverted U-shaped off-set clamping members 13 provided with re-inforcing ribs 14 and clamping screws 15, said screws being carried by those portions of the clamping members alining with the upper ends of the brackets, or, in other words, the screws are at the rear sides of the brackets and are adapted to engage the rear face of a tray wall 16 over the upper edge of which the clamping members 13 are mounted. The clamping members 13 permit of the bib being alined with the rear face of the tray wall 16 or with the front face thereof, it being only necessary to reverse the clamping members from the position shown and this may be necessary in such instances where there must be wall clearance.

By reference to Fig. 2 it will be noted that the bib presents a clean cut appearance with no interstices in which dirt and other matter may accumulate, and by reason of the brackets alining with the pipe connections there is clearance or a wide range of action for the swivel spout or outlet member 4 of the bib.

It is thought the utility of my invention will be apparent without further description, and while in the drawing there is illustrated a preferred embodiment of my invention, it is to be understood that the struc-

tural elements are susceptible to such variations and modifications as fall within the scope of the appended claims.

What I claim is:—

- 5 1. The combination of a bib, depending channel shaped lugs carried thereby, supporting brackets for said bib, said brackets vertically alining with said lugs and extending into the channels thereof, and fastening 10 means extending through said lugs and brackets to connect said lugs to said brackets.
2. The combination of a bib fitting adapted to be secured to a tray wall, reversible brackets alining with said fitting and extending behind the tray wall and adapted 15 when reversed to bring the fitting over the tray, means connecting said brackets to said

fitting, and means extending outwardly at right angles to said brackets and over the tray wall adapted for connecting said brackets to said tray wall in either position.

3. The combination of a bib, depending lugs carried thereby, supporting brackets for said bib, said brackets vertically alining with said lugs and extending into engagement therewith, and fastening means extending through said lugs and brackets to connect said lugs to said brackets.

In testimony whereof I affix my signature in presence of two witnesses.

OSCAR P. BENJAMIN.
